UNITED STATES PATENT OFFICE.

HENRY D. COTTER AND JOSEPH W. A. GARDAM, OF NEW YORK, N. Y.

DESIGN FOR A CASING FOR COMPASSES.

SPECIFICATION forming part of Design No. 32,770, dated June 5, 1900.

Application filed January 11, 1898. Serial No. 666,374. Term of patent 14 years.

To all whom it may concern:

Be it known that we, HENRY D. COTTER, a subject of Her Majesty the Queen of Great Britain, and JOSEPH W. A. GARDAM, a citizen of the United States, both residing at New York, (Brooklyn,) in the county of Kings and State of New York, have invented and produced a new and original Design for a Casing for Compasses, of which the following is

10 a specification, reference being had to the accompanying drawing, forming a part thereof.

The leading feature of our design is the ornamental structure shown in the accompanying drawing, wherein A is a globular body

15 having an inner ring or band B and an outer band or ring D, with their faces disposed at right angles to each other, a projection E at the top, and a standard C, extending from the inner ring B and terminating near the axis, as shown.

20

What we claim is—

The design for a casing for a compass, substantially as shown and described.

HENRY D. COTTER.
JOSEPH W. A. GARDAM.
